(57) **CLAIM**

We claim the ornamental design for a folding knife, as shown and described.

DESCRIPTION

FIG. 1 is a front perspective view of a folding knife, showing our new design;

FIG. 2 is a right side view thereof;

FIG. 3 is a left side view thereof;

FIG. 4 is a bottom view thereof;

FIG. 5 is a top view thereof;

FIG. 6 is a front view thereof; and,

FIG. 7 is a rear view thereof.

The broken lines depict portions of the folding knife in which the design is embodied that form no part of the claimed design.
